United States Patent Office

Des. 209,814
Patented Jan. 9, 1968

209,814

PULL

Leland George Stone, Mundelein, Ill., assignor to Amerock Corporation, Rockford, Ill., a corporation of Connecticut

Filed Apr. 24, 1967, Ser. No. 6,817

Term of patent 14 years

(Cl. D10—8)

FIG. 1 is a front elevation of a pull incorporating my new design.

FIG. 2 is a top view of the pull.

FIG. 3 is a side view as seen from the right of FIG. 1.

FIG. 4 is an enlarged sectional view taken along the line 4—4 in FIG. 3.

FIG. 5 is an enlarged sectional view taken along the line 5—5 in FIG. 3.

FIG. 6 is an enlarged sectional view taken along the line 6—6 in FIG. 3.

I claim:
The ornamental design for a pull, as shown.
